(57) **CLAIM**

The ornamental design for a key, as shown and described.

DESCRIPTION

FIG. 1 is a front elevational view of the key of the present invention showing my new design and showing the handle in phantom;

FIG. 2 is a rear elevational view thereof;

FIG. 3 is a right side view thereof;

FIG. 4 is a left side view thereof;

FIG. 5 is a bottom view thereof;

FIG. 6 is a top view thereof;

FIG. 7 is a perspective view thereof; and,

FIG. 8 is a cross-sectional view thereof taken along line 8—8 of FIG. 7.

The broken line showing is included for the purpose of illustrating and forms no part of the claimed design.

1 Claim, 2 Drawing Sheets

FIG. 6

FIG. 8

FIG. 5

FIG. 7
